REFRIGERATING APPARATUS

Andrew A. Kucher, Dayton, Ohio, assignor to
 General Motors Corporation, Dayton, Ohio, a
 corporation of Delaware

Application February 28, 1940, Serial No. 321,269

9 Claims. (Cl. 257—3)

This invention relates to refrigeration and more particularly to an improved refrigeration system for use in air conditioning systems.

One object of this invention is to provide a portable air conditioning unit which comprises a plurality of individual sections which may be readily assembled as a unit at the point of use.

An object of this invention is to provide a new and improved apparatus for conditioning the air for private homes and the like.

Another object of this invention is to provide an improved arrangement for distributing the conditioned air to a plurality of separate rooms.

Still another object of my invention is to provide an air conditioning system having improved acoustical features.

Still another object of this invention is to provide a new combination of elements which makes it possible to use the refrigerating system a greater portion of the year.

A further object of this invention is to provide an improved control system for the air conditioning apparatus.

Further objects and advantages of the present invention will be apparent from the following description, reference being had to the accompanying drawings, wherein a preferred form of the present invention is clearly shown.

In the drawings:

Fig. 1 is a top view of the air conditioning apparatus with parts broken away so as to show the arrangement of the elements within the cabinet;

Fig. 2 is an elevational view of the same with parts broken away;

Fig. 3 is a perspective view showing the sectional unit which supports the volatile refrigerating system;

Fig. 4 is a perspective view showing another sectional unit which supports the water coil and the air filter;

Fig. 5 is a perspective view showing the blower unit;

Fig. 6 is a diagrammatic view showing the controls;

Fig. 7 is a view partly in elevation and partly in section showing the arrangement of the air conditioning unit with respect to the air discharge panel; and

Fig. 8 is a fragmentary sectional view taken on line 8—8 of Fig. 6 showing the inlet and outlet port arrangement of the compressor.

While I have shown my invention applied to a portable air conditioning unit primarily designed for conditioning air for private homes and the

like, it is to be understood that several of the features of my invention are of general application. In the particular embodiment shown, the air conditioning unit generally designated by the reference character 10 comprises a plurality of sections 12, 14, 16 and 18 which are so designed as to be assembled at the point of use. As best shown in Fig. 3 the section 12 comprises a refrigerant evaporator 20, a water-cooled motor-compressor-condenser unit 22 and a casing member 24 which forms one portion of the exterior casing of the completed unit. The casing member 24 supports the entire volatile refrigerant system including the evaporator 20, the water-cooled motor-compressor-condenser unit 22, the fixed restrictor 21, and all the connecting refrigerant lines. These units, as will be pointed out hereinafter, are of light weight compact design whereby that portion of the system which is supported by the casing section 24 is of relatively light weight and small in size so that it may be carried up and down stairways and, if necessary, passed through relatively small windows or other openings.

As shown in Fig. 4 section 14 comprises an outer shell 26 which supports a water coil 28. As shown in Figs. 1 and 2 a filter element 32 is also carried by the section 14 and is disposed between the louvered air inlet opening 30 and the water coil 28.

The sections 12 and 14 rest on the base sections 16 and 18 which are designed so as to deaden the noises produced by the compressor and the blower mechanism. The blower 34 and the blower motor 36 are removably supported on the section 16 and may be transported separately from the section 16. The sections 16 and 18 are lined with sound-deadening material 38 so as to absorb noises produced by the mechanical parts of the system and noises produced by the air flowing through the unit. By virtue of the above described arrangement, each of the sections 12, 14, 16 and 18 may be separately carried to the point of use and may be assembled at the point of use with very little difficulty. A pair of cover members 40 serve to enclose the upper side of the sections 12 and 14 and also assist in holding the sections 12 and 14 in proper relationship. Any convenient means such as bolts or the like may be provided for further securing the sections together.

In the preferred arrangement the air conditioning unit is intended to be mounted directly within the attic space or the like of a private home. The air to be conditioned is admitted to the attic space from the outside through one of

the attic windows or any conventional air inlet leading to the attic. The air is first caused to enter the air conditioning unit through the opening 30 and then passes through the filter 32 into thermal exchange relationship with the water coil 28 and the evaporator 20. The air thus cooled is then picked up by the blower 34 and is discharged into the sound-deadening section 16 from whence it flows into section 18 through the openings 42 and 44 located at opposite ends of the baffle 45 of the section 16. Rather than providing special air ducts for distributing the conditioned air to the various rooms, the hallways, stairways, door openings, windows and, in some cases, booster fans are relied on to distribute the conditioned air. The conditioned air leaving the chamber 18 discharges downwardly through an opening 46 which is in registry with the passage 48 leading to an air distributing grille arrangement 50 preferably secured to the first or second floor hall ceiling depending upon the type of home being conditioned. As shown in Fig. 7 the air leaving the discharge grille 50 is caused to flow substantially horizontally along the ceiling until striking the side walls of the hall from whence the air sweeps downwardly in front of any doorways or other openings leading to rooms adjoining the hallway. Inasmuch as this apparatus is designed for use in many different types of homes, no special arrangement of hallways, rooms, etc., has been shown as this will be different in practically every home.

In order to obtain proper distribution of the air into the various rooms of the home the necessary doors and windows are left open so as to provide the necessary flow of air. It should be noted that this air conditioning system is designed primarily to condition fresh air only and therefore no means has been provided for returning the air from the rooms to the inlet of the conditioning unit. Under certain circumstances, however, it may be desirable to provide means for recirculating a portion of the air from the rooms. Any conventional means may be used for recirculating a portion of the air if desired.

In order to increase the usefulness of the volatile refrigerating system and the water coil, a novel control arrangement has been provided as shown in Fig. 6 whereby the refrigerating apparatus and the water coil may be used for either heating or cooling the incoming air as explained hereinafter.

In many localities there are certain times of the year when the temperature falls below that desired for comfort without becoming cold enough to require the operation of the usual winter heating system. At such times it is intended that the apparatus disclosed herein will serve to temper the air sufficiently to produce comfort.

The water temperature in most localities is sufficiently near the air temperature desired so that this water may be used for cooling hot outside air during the hot weather and it may likewise be used for increasing the temperature of cold outside air during the colder weather. So long as the water temperature is below the outside air temperature this water can be used in cooling the air. Likewise, so long as the water temperature is above the outside air temperature, this water may be used for imparting heat to the air.

The controls provided make it possible to utilize the water coil not only during the cooling cycle but also during the heating cycle. Water

from any suitable source such as the city water mains enters the unit through the line 52 which connects to the branch lines 54 and 56, which are provided with the pressure actuated valves 58 and 60 respectively. The branch lines 54 and 56 communicate with the line 62 leading to the three-way solenoid valve 64 which directs the incoming water either through the water coil 28 or the by-pass 66 around the water coil 28. The three-way valve 64, when energized, causes the water to flow through the by-pass and when de-energized causes the water to flow through the water coil 28. The water, after flowing through the coil 28 or the by-pass 66, enters line 68 which conveys the water to the condensing coil 70 located within the hermetically sealed casing 72 of the motor-compressor-condenser unit 22. During the cooling cycle the high pressure refrigerant condenses on the outer surface of the coil 70 located within the condensing cavity 71. The water leaving the coils 70 discharges into the drain line 74 which may also serve to drain away the condensate collecting in the drip pans 76 and 78 (see Fig. 1). The drip pans are provided with drain pipes 80 and 82 which may be connected either to the drain 74 or to a separate drain.

The volatile refrigerant system which includes the heat exchanger 20, the fixed restrictor 21 and the motor-compressor-condenser unit 22 is designed so as to be capable of operation as a reverse cycle refrigerant system. By using a volatile refrigerant system in which the flow of refrigerant between the condenser and the evaporator are controlled by a fixed restrictor and in which the compressor is capable of operating in either direction so as to cause that heat exchange element which normally serves as an evaporator to serve as a condenser, it is possible to use a simple volatile refrigerant system for either cooling the air or heating the air. The fixed restrictor 21 may be of the type disclosed in the Kucher Patent 2,063,745, or of any other conventional fixed restrictor design. It is important, however, to use a fixed restrictor as distinguished from an expansion valve in which the flow of refrigerant through the valve is controlled by the evaporator pressure. By using a fixed restrictor, it is possible to reverse the refrigerant cycle without providing any valves or the like for reconnecting the refrigerant flow control means into the refrigerant circuit. The coils of the heat exchanger 20 are arranged so as to permit the refrigerant condensed therein to drain into the line leading to the fixed restrictor 21. Inasmuch as this system is designed primarily for cooling the air, I have provided a compressor which is so designed as to operate more efficiently during the cooling cycle than during the heating cycle. In the ordinary four-vane compressor, a considerable sacrifice in efficiency results when the inlet port and the outlet port are of equal circumferential extent. As shown in Fig. 8, the compressor comprises a conventional four-vane rotor 84 which operates within the pumping cylinder 86. The rotor 84 is operated by the electric motor 87 having a stator 89 and a rotor 90 located within the hermetically sealed casing 12. During the cooling cycle, when the heat exchange coil 20 serves as an evaporator, the port 92 serves as the inlet port and the port 94 serves as the outlet port. During the heating cycle the port 94 serves as the inlet port and the port 92 serves as the outlet port. An auxiliary port 96 having a

reed-type valve 98 is provided as an excess pressure relief means during the starting of the compressor for the cooling cycle.

The direction of rotation of the motor 90 and consequently the direction of rotation of the four-vane rotary pump element 84 is controlled by a thermostat 100. Any conventional motor which is capable of operating in either direction may be used. Inasmuch as motors of this type are well known in the art, the specific details of the motor have not been described in detail. This instrument may be located so as to respond either to the outside temperature or the inside temperature. The bulb 100 is connected to the bellows 102 which actuates the motor reversing switch mechanism 104 and the switch 106. The switches 104 and 106 are shown in the position calling for cooling.

Inasmuch as there may be times when neither heating nor cooling is required, a separate thermostat 108 is provided which turns on and off the entire system. This element 108 may be located either inside or outside, preferably inside, however.

In order to control the three-way valve 64 which controls the flow of water through the water coil 28, I have provided a switch 110 which is operated by a pair of opposed bellows 112 and 114. The bellows 112 communicates with the thermostatic bulb 116 filled with a volatile fluid and placed so as to respond to the temperature condition of the incoming air. The bellows 114 is controlled by a similar thermostat bulb 118 which is responsive to the temperature of the incoming water.

With the switch 106 in the position shown, the solenoid valve 64 will be energized when a circuit is closed between the contact 120 and the contact 122. The contact 120 engages the contact 122 whenever the temperature of the incoming water is high and the temperature of the incoming air is low. By virtue of this arrangement, when cooling is desired the water is caused to by-pass the coil 28 at such times when the water temperature is high and the incoming air temperature is low, under which conditions the water would be of no assistance in cooling the air.

Whenever the air conditions cause the switch 106 to move to the opposite position from that shown in Fig. 6, the solenoid valve 64 is energized only when the contact 120 is in engagement with the contact 124. By virtue of the arrangement described hereinabove, the circuit between 120 and 124 is closed only at such times when the temperature of the outside air is high and the temperature of the incoming water is low. The purpose of this arrangement is to avoid contacting a stream of relatively warm air with water at a lower temperature when heating is required.

The amount of water flowing through the water line 62 and consequently the coil 28 or by-pass 66 and the water condensing coil 70 is under control of the pressure responsive valves 58 and 60. These valves respond to the refrigerant pressure within the refrigerant system. The valve 60 responds to the pressure in a line leading from the fixed restrictor 21 to the heat exchange coil 20, whereas the valve 58 responds to the pressure in the line leading from the condensing cavity 71 and the restrictor 21. These valves are designed to open wider as the pressure within the refrigerant system increases. By virtue of the

arrangement shown each valve functions as a conventional head pressure responsive valve.

During the cooling cycle the refrigerant in the line leading from the fixed restrictor to the evaporator 20 is low, and therefore the valve 60 will be closed. The valve 58, however, will respond to the pressure in the line leading from the condensing chamber 71 to the fixed restrictor 21 which corresponds to the condenser pressure. Consequently, as the condensing pressure increases, the valve 58 will admit more water through the water lines. As the cycle reverses and the volatile refrigerant system is used for heating the air, the pressure in line 59 becomes low and the valve 58 closes, whereas the pressure in line 61 will correspond to the condenser pressure with the result that the valve 60 will be open an amount corresponding to the condenser pressure.

In order to simplify the disclosure, only conventional dry bulb control instruments have been shown. It is within the purview of this invention, however, to use other types of controls such as wet bulb, humidity or effective temperature controls.

While the form of embodiment of the invention as herein disclosed, constitutes a preferred form, it is to be understood that other forms might be adopted, all coming within the scope of the claims which follow.

What is claimed is as follows:

1. A conditioning unit of the type adapted to be used in conditioning air for private homes and the like comprising in combination; a complete volatile refrigerant system; a water coil; thermostatic control means for controlling the operation of said refrigerant system; and means for controlling the flow of water through said water coil comprising a first means responsive to a refrigerant pressure within said refrigerant system and a second means responsive to both the air temperature and the water temperature.

2. In combination, means for circulating a stream of air to be conditioned, a first heat exchange element in thermal exchange relationship with said stream, a second heat exchange element in thermal exchange relation with said stream, means for circulating a volatile refrigerant through said first heat exchange element,

means for circulating water through said second heat exchange element when either heating or cooling of the air is required, means preventing flow of water through said second heat exchange element when cooling is required and the water temperature is high and the incoming air temperature is low, and means preventing flow of water through said second heat exchange element when heating is required and the water temperature is low and the incoming air temperature is high.

3. In combination; a pair of complementary heat exchange units; a multiple vane rotary compressor unit adapted for reversing the direction of flow of refrigerant through said heat exchange units; said compressor comprising means forming a pumping chamber, a multiple vane rotor within said chamber, a motor for operating said rotor, means for reversing the direction of rotation of said motor, inlet and outlet ports in said first named means, one of said ports extending a greater circumferential distance than the other of said ports whereby said compressor has a greater displacement when operating in the one direction than when operating in the other direction.

4. A portable air conditioning unit of the type adapted to be used in conditioning air for private homes and the like comprising in combination, a plurality of sectional elements adapted to be assembled as a unit at the point of use, two of said sections comprising an air discharge means lined with sound-deadening material, another of said sections comprising a complete volatile refrigerant system supported on said air discharge means, and still another of said sections comprising a water coil supported on said air discharge means beside said volatile refrigerant system, said water coil section comprising an air inlet, said volatile refrigerant section comprising means for discharging the air downwardly into said air discharge means.

5. A portable air conditioning unit for conditioning air for private homes and the like comprising in combination, a cabinet, an air inlet in said cabinet, a water coil adjacent said inlet, a reverse cycle volatile refrigerant system mounted within said cabinet, means for forcibly flowing a stream of fresh air in thermal exchange relationship with said water coil and thereafter with a portion of said volatile refrigerant system, means for discharging the conditioned air into the space to be conditioned, means responsive to the outside air temperature for reversing the cycle, and means responsive to the inside air temperature for starting and stopping the operation of said volatile refrigerant system.

6. In combination; a pair of complementary heat exchange units; a multiple vane rotary compressor unit adapted for reversing the direction of flow of refrigerant through said heat exchange units; said compressor comprising means forming a pumping chamber, a multiple vane rotor within said chamber, a motor for operating said rotor, means for reversing the direction of rotation of said rotor, inlet and outlet ports in said first named means, one of said ports extending a greater circumferential distance than the other of said ports whereby said compressor has a greater displacement when operating in the one direction than when operating in the other direction.

7. A portable air conditioning unit for condi-

tioning fresh outside air for private homes and the like comprising in combination, a cabinet adapted to be mounted above the space to be conditioned, a volatile refrigerant system mounted within said cabinet and including a fixed restrictor and a reversible compressor for reversing the flow of refrigerant through said restrictor, means for forcibly flowing a stream of fresh air in thermal exchange relationship with a portion of said volatile refrigerant system, means for discharging the conditioned air downwardly into the space therebelow, and means for circulating a stream of water in thermal exchange relationship with incoming air and thereafter in thermal exchange relationship with refrigerant in said refrigerant system whereby said water first contacts said air and thereafter said refrigerant.

8. In combination, means for circulating a stream of air to be conditioned, a first heat exchange element in thermal exchange relationship with said stream, a second heat exchange element in thermal exchange relationship with said stream, means for circulating a volatile refrigerant through said first heat exchange element, means for circulating water through said second heat exchange element when either heating or cooling of the air is required, and means preventing flow of water through said second heat exchange element when heating is required and the water temperature is low and the incoming air temperature is high.

9. A portable air conditioning unit of the type adapted to be used in conditioning air for private homes and the like comprising in combination, a plurality of sectional elements adapted to be assembled as a unit at the point of use, an air discharge means lined with sound-deadening material, another of said sections comprising a complete volatile refrigerant system supported on said air discharge means, and still another of said sections comprising a water coil supported on said air discharge means beside said volatile refrigerant system, said water coil section comprising an air inlet, said volatile refrigerant section comprising means for discharging the air downwardly into said air discharge means.

ANDREW A. KUCHER.
